UNITED STATES PATENT OFFICE.

CHARLES K. THEOBALD, OF JONESBORO, ARKANSAS.

ELECTRIC-FIXTURE-DISPLAY DEVICE.

1,418,215.

Specification of Letters Patent. Patented May 30, 1922.

Application filed October 12, 1921. Serial No. 507,319.

To all whom it may concern:

Be it known that I, CHARLES K. THEOBALD, a citizen of the United States, residing at Jonesboro, in the county of Craighead and 5 State of Arkansas, have invented certain new and useful Improvements in Electric-Fixture-Display Devices, of which the following is a specification, reference being had to the accompanying drawings.

10 This invention relates to display devices and has for its object the provision of mechanism for use in the show room of electric fixture dealers whereby fixtures may be successively displayed in an attractive manner.

15 Ordinarily fixtures on display in the exhibition rooms or stores of dealers of this character are suspended from the ceiling in great profusion and when a prospective purchaser desires to inspect the different fixtures 20 the large number of them frequently causes confusion especially as it is impossible to view one particular fixture by itself. The artistic effect is also destroyed.

It is with the above facts in view that I 25 have designed the present invention which contemplates the provision of means whereby selected fixtures may be successively lowered through a hole in a false ceiling built into the display room so that only one fixture 30 will be seen at a time and so the entire artistic effect may be had and the article be displayed in a pleasing and attractive manner.

More specifically the invention resides in the provision of a rotatable support carrying 35 a series of arms from which the different fixtures are suspended above the false ceiling, the construction being such that any one fixture may be brought into registration with a hole in the false ceiling and lowered there- 40 through.

Another object is the provision of a novel locking device associated with the fixture carrying arms whereby to hold them at the proper position with the fixture in exact registration with the hole, this locking means 45 acting automatically and being manually releasable when it is desired to display a different fixture.

A further object is the provision of guide 50 means whereby not only to insure the proper centering of the fixture with respect to the hole in the sub-ceiling but also to insure proper descent of the fixture through the hole without permitting any twisting or 55 turning.

Still another object is the provision of automatic means whereby the fixture will be lighted when it reaches its display position, the lights being extinguished when the fixture is subsequently raised out of the hole, 60 this lighting means involving the provision of a plurality of suitably connected electric contacts with one of which is associated an auxiliary contact for automatically energizing an ordinary ceiling light in the display room when the lights of the fixture displayed are extinguished. 65

A still further object is the provision of indicating means associated with the rotary support whereby the operator will know 70 definitely in advance exactly which fixture is being lowered.

An additional object is the provision of mechanism of this character which will be comparatively simple in construction, easy 75 to install, highly efficient in use, attractive in effect and a general improvement in the art.

With the above and other objects and advantages in view, the invention consists in 80 the details of construction to be hereinafter more fully described and claimed, and illustrated in the accompanying drawings, in which:

Figure 1 is a diagrammatic view of a display room showing a possible location of my mechanism; 85

Figure 2 is a vertical sectional view through the room showing my device in position; 90

Figure 3 is a horizontal sectional view looking upwardly toward the true ceiling and illustrating my locking device;

Figure 4 is a detail perspective view showing the guide means for controlling the descent of the fixtures; 95

Figure 5 is a cross sectional view through the false ceiling and showing the electrical contacts and a diagram of the circuit; and

Figures 6, 7 and 8 are detail views. 100

Referring more particularly to the drawings, I have shown, in Figure 1, a possible and convenient arrangement of a display room. In this figure I have illustrated the display room A as sub-divided into a plurality of small rooms B which may be, if preferred, furnished in different ways, for instance to represent a dining room, bed room, music room and living room so that when fixtures are displayed in any of the 105 110

small rooms the effect will be harmonious and the true artistic value of the fixture may be fully appreciated. It is, however, to be understood that there is no special limitation as to such an arrangement. In any event, however, it is necessary to provide a display room with a false or sub-ceiling designated by the numeral 10, this false ceiling being spaced somewhat below the true 5 ceiling C and being of any conventional or preferred construction but naturally including suitable joists 11 covered by a sheathing 12. At whatever point it is desired to display fixtures this false ceiling 10 would be provided with a circular hole 13 preferably surrounded by a more or less ornamental molding 14.

In the further carrying out of the invention I provide an upright post 15 which is located 20 at some convenient point in the display room and which is provided at its upper and lower ends with pivot points operating within suitable bearings 16 located upon the true ceiling C and upon the floor D. It is of course understood that the lower bearing be either of the ball or roller type so that the weight of the post and mechanism carried thereby will be materially supported while at the same time the post may be easily rotated. 25 Secured upon the upper portion of the post, that is above the false ceiling 10, is a series of radial arms 17 of any preferred construction and of any suitable length and these arms are preferably reinforced by 30 braces 18. The arms must of course be of such length that they will reach from the post to a point immediately above the hole 13 in the sub-ceiling. In Figure 1 I have shown the post as located centrally of the 35 four small rooms each of which has its sub-ceiling provided with a hole through which fixtures may be displayed as will be hereinafter described.

Mounted upon the free ends of the arms 17 40 are pulleys 19 over which are trained flexible members 20 which may be small cables, ropes, wires or the like and these flexible members lead downwardly along the post to points near the lower end thereof, the 45 extremities of the flexible members carrying rings 22 engaged upon suitable hooks 23 projecting from the periphery of the post. The other ends of the flexible members carry the fixtures to be displayed, one of such fixtures being shown at E. It is preferable that the post have inscribed thereon a series of 50 numbers adjacent the flexible members extending there along and it may also be advisable to provide a ring or disk 24 secured upon the post immediately below the hooks 23, this disk being likewise inscribed with 55 numbers corresponding to those first mentioned so that the operator may tell at a glance which particular fixture is associated 60 with each individual flexible member. It

should also be mentioned that the post is preferably provided with a series of handles 25 by means of which it may be turned to bring the different fixtures successively above the hole 13.

The suspension means for each fixture consists of a circular disk 26 of wall board or the like of a size to pass through the hole 13 and be retained upon the molding 14. This disk is of course secured to both the fixture and the associated flexible member. It is preferable to provide a plurality of upwardly and outwardly curved guides 27 which are located at the edge of the hole 13 and which are engaged by the disk 26 when a fixture is lowered so that the disk will be properly led into the hole 13. It is of course to be observed that the fixture is lowered simply by unhooking the ring 22 of the associated flexible member from the hook 23 and allowing the fixture to descend by gravity.

It is held desirable to provide means for holding the arms 17 stationary with the fixture desired to be displayed immediately above the hole 13 and in exact alignment therewith. In order to accomplish this I provide a pair of elongated bars 28 pivoted upon the ceiling C at such a position that their adjacent ends will be disposed above the hole 13. The adjacent ends are spaced very slightly apart and are designed to receive between them whichever arm 17 carries the fixture to be immediately displayed. These bars have curved edges 29 leading to the space between their adjacent ends so that they will swing upon their pivot points when initially engaged by an arm 17 and allow the arm to slip into the space between the ends. It is of course conceivable that these bars might be pivoted in different ways though I have shown the pivot points 30 as being intermediate their ends. It is also to be understood that I might make use of springs normally holding the bars in one position though in actual practice I prefer to provide flexible members 31 connected with the free ends of the bars, trained over guide pulleys 32 and carrying weights 33. When an arm 17 is engaged between the bars 29 it is apparent that the fixture will be located in the exact proper position above the hole 13.

In order to release this locking mechanism to permit turning of the post for displaying successive fixtures, I make use of a flexible member 34 which is trained over suitable guide pulleys 35 and which has one end branched, as indicated at 36, and connected with both of the bars 29 at the adjacent ends thereof. This flexible member is trained down alongside the post 10 and has its lower end connected with a treadle 27 mounted upon the floor adjacent the bottom of the post. When the operator presses upon the treadle 37 both of the bars 29 will

be swung out of engagement with the handle 17 so as to permit the post to be turned. As soon as pressure upon the treadle is released the weights 33 will return the bars 29 to normal position so that they will automatically engage the next arm 17 as it comes around. When a fixture is lowered it is desirable to provide some means for preventing it from turning or twisting and to accomplish this I provide a board 38 secured in edge-wise position transversely of the disk 26 with its ends projecting slightly beyond the disk and shod with copper strips 39 for a purpose to be described. Secured to this board 38 is a transversely disposed board 40 which has one end carrying an arm 41 engageable between spaced upright guides 42 secured upon the sub-ceiling. The upper ends of these guides are provided with diverging strips 43 which define a flaring entrance opening to the space between the guides so as to lead the arm 41 properly into position as the fixture is lowered. It may be advisable to provide anti-friction rollers 44 on the arm 41 for the purpose of insuring free and easy movement. Hinged upon the board 38 is a board 45 which is formed with an elongated slot 46 engaging upon a bar 47 depending from the arm 17. Located within the slot 46 is a roller 48 engaging against an edge of the bar 47 for insuring free and easy movement.

I consider it preferable to provide means for automatically energizing the electric light bulbs within the fixture so that when the fixture reaches its display position with the disk 26 fitting snugly within the hole 13 illumination will occur. In order to accomplish this I provide a pair of V-shaped contacts 49 located at diametrically opposite points at the edge of the hole 13 and insulated from the wood work by means of suitable slate bases 50. These contacts 49 are so located as to be engaged by the copper strips 39 on the ends of the board 38. Connected with the copper strips are wires 51 and 52 which lead through the fixtures to the sockets thereof in the usual manner. In conjunction with these contacts I employ a switch including a base 53 of insulating material mounted near one of the contacts 49 and rising from this base 53 is a post 54 upon which is pivoted a switch blade 55 engageable with a contact 56. Connected with the blade 55 and with the base 53 is a retractile coil spring 57 which normally holds the switch blade 55 in engagement with the contact 56. The blade 55 is provided with an extension 58 which extends within the adjacent contact 49 whereby to be engaged by the copper strip 39 at one end of the board 38. The numeral 59 designates an ordinary incandescent lamp of the ceiling type which is located at some convenient point within the display room. The numerals

60 and 61 designate the electric lighting wires of the building, the former of which is connected with the post 54 and the latter of which is connected with one terminal of the socket of the lamp 59. The other terminal of the socket of the lamp 59 is connected by a wire 62 with the contact 56. Connected with the wire 61 is a wire 63 which is connected with one of the contacts 49.

The operation of the device is as follows: Initially all the fixtures are of course suspended from the arms 17 between the sub-ceiling 10 and the true ceiling C. Assuming that a certain fixture is to be displayed, the operator grasps one or more of the arms 25 and turns the post 15 to bring the arm 17 carrying the desired fixture immediately above the hole 13. This is determined by means of the numbers on the disk 24, it being of course apparent that the pointer arm 24a cooperates with marks on this disk or ring so that this point may be properly determined. As previously stated, the arm 17 thus brought over the hole 13 will engage between the adjacent ends of the locking bars 29 and be held thereby in the exact position it should occupy. The operator then grasps the copper ring 22 and unhooks it from the hook 23 and allows the fixture associated therewith to descend. As the fixture moves downwardly the arm 41 will pass between the outwardly curved strips 43 and be guided thereby into the space between the guides 42, while at the same time the slotted board 45 will slide down along the bar 47 depending from the associated arm 17. This will prevent any turning or twisting of the fixture while it is being lowered. As the fixture nears its lowered position the disk 26 will engage the curved guide strips 27 and be led into the hole 13 so that it may rest upon the molding 14. At the same time the copper strips 39 at the end of the board 38 will enter the V-shaped contacts 49, one copper strip engaging the extension 58, one contact 49, through the wire 51 and the lamps in the fixture, back through the wire 52 and the other contact 49 and thence through the wire 63 to the wire 61 back to the source. This will, of course, result in energizing the bulbs in the fixture so that the fixture will be illuminated to get the proper effect.

When it is desired to display another fixture, the operator depresses the treadle 37 to effect a pull upon the flexible member 34 which swings the bars 29 out of engagement with the arm 17. It is of course understood that the fixture previously displayed should be pulled up into its initial position by simply pulling down upon the associated flexible member and hooking the ring thereon on to the hook 23 from which it had previously been removed. After the locking means has

100

105

110

115

120

125

130

been released by the treadle mechanism the operator may turn the post 15 to bring any other desired fixture directly over the hole 13 whereupon this other fixture may be lowered in the same manner as previously described. After the fixture has been displayed and is moved upwardly it will be apparent that the coil spring 57 will operate to swing the blade 55 so that the extension 10 58 will be out of engagement with the associated contact 49 and so that the blades 55 will engage the contact 56. When this occurs it is of course apparent that the lamps in the fixture will be deenergized while current will then flow from the wire 60 to the post 54, blade 55, contact 56, wire 62, through the lamp 59 and back through the wire 61 so that the ceiling light will be energized. This action is of course automatic 20 and needs no attention.

From the foregoing description and a study of the drawings it will be apparent that I have thus provided a simply constructed and arranged mechanism whereby 25 electric lighting fixtures may be adequately displayed so that the entire effect and artistic beauty thereof may be appreciated fully. Owing to the automatic illumination of the fixture when it is lowered to display position it will be apparent that every detail 30 of coloring of shades, translucent bowls and in fact everything of this nature may be seen clearly and in a manner which should appeal to the prospective purchaser.

While I have shown and described the preferred embodiment of the invention, it is of course to be readily understood that I reserve the right to make such changes in the form, construction and arrangement of 35 parts as will not depart from the spirit of the invention or the scope of the subjoined claims.

Having thus described my invention, I claim:

45 1. A display device comprising the combination of a false ceiling having a hole therein, of an upright rotatable post carrying a series of arms located above the false ceiling, flexible members trained over pulleys on the arms and being detachably secured at the lower end of the post, said flexible members carrying fixtures to be displayed, said post being rotatable to bring a selected arm and fixture above the hole 50 whereby the fixture may be subsequently lowered by means of the associated flexible member.

60 2. A display device comprising the combination of a false ceiling having a hole therein, of an upright rotatable post carrying a series of arms located above the false ceiling, flexible members trained over pulleys on the arms and being detachably secured at the lower end of the post, said 65 flexible members carrying fixtures to be dis-

played, said post being rotatable to bring a selected arm and fixture above the hole whereby the fixture may be subsequently lowered by means of the associated flexible member, the fixtures having sockets carrying incandescent bulbs, and means for automatically energizing said bulbs when a fixture is in lowered position. 70

3. A display device comprising the combination of a false ceiling having a hole 75 therein, of an upright rotatable post carrying a series of arms located above the false ceiling, flexible members trained over pulleys on the arms and being detachably secured at the lower end of the post, said 80 flexible members carrying fixtures to be displayed, said post being rotatable to bring a selected arm and fixture above the hole whereby the fixture may be subsequently lowered by means of the associated flexible 85 member, the fixtures having sockets carrying incandescent bulbs, means for automatically energizing said bulbs when a fixture is in lowered position, said means comprising contacts located adjacent the hole and connected with a source of current, and a transverse member associated with the fixture and carrying contacts engageable with said first named contacts and connected with the incandescent bulbs. 95

4. A display device comprising the combination of a false ceiling having a hole 100 therein, of an upright rotatable post carrying a series of arms located above the false ceiling, flexible members trained over pulleys on the arms and being detachably secured at the lower portion of the post, said 105 flexible members carrying fixtures to be displayed, said post being rotatable to bring a selected arm and fixture above the hole whereby the fixture may be subsequently lowered by means of the associated flexible member, and guide means associated with each arm whereby to prevent turning of the fixture during descent. 110

5. A display device comprising the combination of a false ceiling having a hole 115 therein, of an upright rotatable post carrying a series of arms located above the false ceiling, flexible members trained over pulleys on the arms and being detachably secured at the lower portion of the post, said 120 flexible members carrying fixtures to be displayed, said post being rotatable to bring a selected arm and fixture above the hole whereby the fixture may be subsequently lowered by means of the associated flexible member, a disk associated with each fixture at the point of connection thereof with the flexible member, a transverse member carried by the disk and having a guide arm, and a pair of spaced upright guides located adjacent the hole and receiving said arm between them. 125

6. A display device comprising the com- 130

bination of a false ceiling having a hole therein, of an upright rotatable post carrying a series of arms located above the false ceiling, flexible members trained over pulleys on the arms and being detachably secured at the lower portion of the post, said flexible members carrying fixtures to be displayed, said post being rotatable to bring a selected arm and fixture above the hole 5 whereby the fixture may be subsequently lowered by means of the associated flexible member, a disk associated with each fixture at the point of connection thereof with the flexible member, a transverse member carried by the disk and having a guide arm, a pair of spaced upright guides located adjacent the hole and receiving said arm between them, a second transverse member carried by the disk, a slotted member hinged 10 upon said second named transverse member, and a bar depending from the associated arm and engaged by said slotted member.

7. A display device of the character described comprising the combination of a false ceiling located within a display room and having a hole, an upright post mounted for rotation and extending above said false ceiling, a plurality of radial arms projecting from the post above the false ceiling, pulleys on said arms, a flexible member trained over each set of pulleys and extending downwardly along the post, the fixture to be displayed being suspended from the flexible members at the ends of the arms, means carried by the post and detachably engaged by the other ends of the flexible members for holding said fixture normally elevated, and a locking device automatically 15 engaging the successive arms when the post is rotated for centering the fixtures above the hole.

8. A display device of the character described comprising the combination of a false ceiling located within a display room and having a hole, an upright post mounted for rotation and extending above said false ceiling, a plurality of radial arms projecting from the post above the false ceiling, pulleys on said arms, a flexible member trained over each set of pulleys and extending downwardly along the post, the fixture to be displayed being suspended from the flexible members at the ends of the arms, means carried by the post and detachably engaged by the other ends of the flexible members for holding said fixture normally elevated, a locking device automatically engaging the successive arms when the post is rotated for centering the fixtures above the hole, and treadle operated means for releasing said locking device.

9. A display device of the character described comprising the combination of a false ceiling located within a display room

and having a hole, an upright post mounted for rotation and extending above said false ceiling, a plurality of radial arms projecting from the post above the false ceiling, pulleys on said arms, a flexible member trained over each set of pulleys and extending downwardly along the post, the fixture to be displayed being suspended from the flexible members at the ends of the arms, means carried by the post and detachably engaged by the other ends of the flexible members for holding said fixture normally elevated, a locking device automatically engaging the successive arms when the post is rotated for centering the fixtures above the hole, said locking device comprising a pair of bars pivoted for swinging movement and having curved edges engageable by the successive arms, and means for moving said bars out of engagement with an arm. 85

10. A display device of the character described comprising the combination of a false ceiling located within a display room and having a hole, an upright post mounted for rotation and extending above said false ceiling, a plurality of radial arms projecting from the post above the false ceiling, pulleys on said arms, a flexible member trained over each set of pulleys and extending downwardly along the post, the fixture to be displayed being suspended from the flexible members at the ends of the arms, means carried by the post and detachably engaged by the other ends of the flexible members for holding said fixture normally elevated, 90 a locking device automatically engaging the successive arms when the post is rotated for centering the fixtures above the hole, said locking device comprising a pair of bars pivoted for swinging movement and having curved edges engageable by the successive arms, means for moving said bars out of engagement with an arm comprising a branched flexible member connected with both bars, trained over guide pulleys and extending down along the post, and means for applying a pull to said last named flexible member. 95

11. A display device for electric fixtures comprising in combination a false ceiling formed with a hole, an upright post carrying radial arms above the false ceiling, said arms carrying electric fixtures to be displayed, said post being rotatable to bring the fixtures successively above the hole, and means for lowering the fixture through the hole. 115

12. A display device for electric fixtures comprising in combination a false ceiling formed with a hole, an upright post carrying radial arms above the false ceiling, said arms carrying electric fixtures to be displayed, said post being rotatable to bring the fixtures successively above the hole, means for lowering the fixture through the 120 130

- hole, and a disk associated with the suspension means of each fixture and designed to enter and close the hole when the fixture is lowered.
- 5 13. A display device for electric fixtures comprising in combination a false ceiling formed with a hole, an upright post carrying radial arms above the false ceiling, said arms carrying electric fixtures to be displayed, said post being rotatable to bring the fixtures successively above the hole, means for lowering the fixture through the hole, a disk associated with the suspension means of each fixture and designed to enter and close the hole when the fixture is lowered, and a plurality of curved upstanding guides located at the edge of the hole for centering said disk.
- 10 14. A display device for electric fixtures comprising in combination a false ceiling formed with a hole, an upright post carrying radial arms above the false ceiling,

said arms carrying electric fixtures to be displayed, said post being rotatable to bring the fixtures successively above the hole, means for lowering the fixtures through the hole, each fixture having sockets carrying incandescent bulbs, an independent incandescent lamp arranged at a remote point, contacts arranged at the edges of said hole, other contacts associated with each fixture and connected with the bulb carrying sockets thereof, a switch device having a movable blade provided with an extension engagable by one of said last named contacts to be moved thereby into engagement with the associated first named contact, said first named contacts and said switch being interposed in a circuit including a source of current and said independent lamp.

In testimony whereof I hereunto affix my signature.

CHARLES K. THEOBALD
